UNITED STATES PATENT OFFICE.

WILLIAM NEUTS, OF HYDE PARK, LONDON, ENGLAND.

COLLAPSIBLE BOX, CASE, AND THE LIKE.

1,308,678.

Specification of Letters Patent.

Patented July 1, 1919.

Application filed March 26, 1919. Serial No. 285,355.

To all whom it may concern:

Be it known that I, WILLIAM NEUTS, a subject of His Majesty the King of England, and resident of Hyde Park, in the county of London, Kingdom of England, have invented certain new and useful Improvements in or Relating to Collapsible Boxes, Cases, and the like, of which the following is a specification.

10 This invention relates to collapsible boxes, cases and the like more especially intended for, but not limited to, use as packing cases and the said invention has for its object to provide an improved collapsible box, or case (hereinafter referred to as case) capable of being used for many purposes such as for packing loose goods or goods in bulk form and for use in packing pulverulent, granular and other material.

15 According to this invention the ends of the box are connected to the side portions thereof in such manner as to allow the bottom of the box which may be hinged to either side to be collapsed or folded upwardly so as to occupy a position between one end and one side of the box when the latter is collapsed. Two diagonally opposite corners of the box are hinged together, the other two diagonally opposite corners being connected together by pivotal means. In collapsing or folding the box one end portion thereof collapses or folds inwardly into a position against the bottom and the other end portion collapses or folds outwardly into a position in alignment with the bottom of the box case and the like. Each end portion may also be connected to its side portion by inside hinges and by a pin and slot connection formed by a bracket or link and a strap passing around the outside surface of the end of the respective side portion and bent over at each end to engage the pin of the pin and slot connection. Secured by hinges to either of the side portions, is a bottom portion which when the case is set up rests against a stop or stops in one side of the case and practically fits the interior of the case.

50 The parts or halves forming the lid of the case may be pivoted or hinged to the end portions or if so desired the said parts may be hinged to or pivotally connected to and/or between bars secured to the end portions. Such pivots may be formed of two plates secured to and between the bars and

projecting from the upper ends thereof, the adjacent part of the lid being provided with suitable plates, sockets or eyes which may be connected by pivot pins to the aforesaid plates.

The two parts of the lid may be prevented from falling into the case when the same is in use by a stop or stops arranged inside the case; or if desired the two parts may be formed with a stop or stops. A suitable recess is provided in the upper faces of the two parts of the lid, these recesses each carrying a hook or hooks, eyes or staples for the attachment of a padlock or other suitable locking device, by which the two parts of the lid can be locked in position.

The sides, lid end portions and bottom of the case may be provided with additional battens or bars for strengthening purposes or for the attachment of the hinges, or pivotal connecting members. In some cases it may be desired to have partly open sides, end portions, lid and bottom.

I will describe with reference to the accompanying drawings constructions in accordance with the present invention but I do not limit myself to the precise construction described and illustrated.

Figure 1 is a plan of a packing case in accordance with the present invention, the packing case being shown collapsed.

Fig. 2 is a side elevation looking in the direction of the arrow, Fig. 1.

Fig. 3 is a perspective view of the complete case and Fig. 4 is a cross section on the line A, B, C.

The same reference numerals wherever repeated indicate the same parts throughout the drawings.

Referring to Figs. 1 to 4 of the drawings 1 and 2 are the side portions, two diagonally disposed ends 3, 4 of the side portions each carrying an end portion 5, 6 hinged together with the respective side portions 1, 2 and each end portion 5, 6 having a pin 7, 8 or half of the lid portion. Each end portion 5, 6 may be connected to its side portion 1, 2 by inside hinges 9 and by a pin 10 and slot 11 formed by a bracket 12 or link and a strap 13 passing around the outside surface of the end of the respective side portion each strap being bent over at one end as at 14, 15 to engage the pin 10 of the pin and slot connection. The two symmetrical portions thus formed are connected by suitable hinges

such as metal straps 18 having projecting brackets 19. Secured by hinges 15 to either of the side portions, is a bottom portion 16 which when the case is set up rests against 5 a stop 17 or stops and practically fits the interior of the case.

The parts 7, 8 or halves forming the lid of the case may be pivoted or hinged to the end portions 5, 6 or if so desired the said parts 10 may be hinged to or pivotally connected at 20, 21 to and between bars 22-23 secured to the end portions. The pivots 20, 21 may be carried by two plates 24, 25 secured to and between the bars 22, 23 and projecting as at 15 26, 27 from the upper ends thereof, the adjacent part of the lid being provided with suitable plates 28, 29, sockets or eyes which may be connected by the pivot pins 20, 21 to the plates 24, 25.

20 The two parts 7, 8 of the lid may be prevented from falling into the case when the same is in use by a stop or stops arranged inside the case; or if desired the two parts may be formed each with a projecting or 25 overlapping portion 31, 32, which insures the simultaneous opening of the two parts forming the lid. A suitable recess 33 is provided in the upper faces of the two parts of the lid, these recesses each carrying a hook 34, 35 or hooks, eyes or staples for the attachment of a padlock or other suitable locking device, by which the two parts of the lid can be locked in position.

The sides, lid, end portions and bottom 35 of the case may be provided with additional battens or bars such as 36 for strengthening purposes or for the attachment of the hinges or pivotal connecting members. In some cases it may be desired to have partly open 40 sides, end portions, lid and bottom.

45 It will thus be seen that on removing the locking device the case can be readily and quickly collapsed, one side and one end portion forming one side of the collapsed case and the other side and the remaining end portion forming the other side of the collapsed case the two parts of the lid portions being folded or turned outwardly over the respective supporting end portion, and the 50 bottom folding or collapsing upwardly against the side to which the said bottom is hinged.

A packing and/or like case constructed in accordance with this invention may be made 55 of metal and/or wood or other suitable material and can be repeatedly used for a con-

siderable length of time before becoming unfit for further use or broken up for fire-wood.

What I claim is:—

60 1. A collapsible box or the like, comprising side members, end members hinged to the side members at the ends of the side members, said end members having outer vertical bars secured thereto, top sections, 65 hinges connecting the outer ends of the top sections and the outer bars of the end members, said hinges having their pivots disposed outwardly of the end members whereby such end members serve to prevent the 70 downward movement of the top sections beyond a substantially horizontal position, the free ends of the top sections having alternately projecting portions overlapping each other so that the top sections are simultane- 75 ously elevated.

2. A collapsible box or the like, comprising side members, end members hinged to the side members at the ends of the side members, said end members having outer 80 vertical bars secured thereto, top sections having outer longitudinal strips, hinges connecting the outer ends of the strips of the top sections and the outer bars of the end members, said hinges having their pivots 85 disposed outwardly of the end members whereby said end members serve to prevent the downward movement of the top sections beyond a substantially horizontal position, the strips of the top sections being provided 90 at their free ends with recesses, said strips projecting beyond their top sections at the opposite edges of the strips so that such projections overlap the top sections and cause them to move upwardly together. 95

3. A collapsible box or the like, comprising side members, L-shaped brackets secured to the ends of the side members and having their transverse portions projecting inwardly, end members hinged to the trans- 100 verse portions of the L-shaped brackets, links pivotally connected to the opposite ends of end members, strips secured to the ends of the side members and having their free ends bent laterally, pins carried by the 105 bent ends of the strips and operating within curved slots in the links, a bottom member arranged between the side members, and a top for the box.

In testimony whereof I have hereunto 110 signed my name.

WILLIAM NEUTS.
